UNITED STATES PATENT OFFICE.

MATTIE E. BLOOD, OF HILLSBORO UPPER VILLAGE, NEW HAMPSHIRE.

SEWING-MACHINE GAGE.

1,278,296.

Specification of Letters Patent. Patented Sept. 10, 1918.

Application filed February 7, 1918. Serial No. 215,842.

To all whom it may concern:

Be it known that I, MATTIE E. BLOOD, a citizen of the United States, residing at Hillsboro Upper Village, in the county of Hillsborough and State of New Hampshire, have invented certain new and useful Improvements in Sewing-Machine Gages, of which the following is a specification.

This invention relates to sewing machines, and more especially to guides along which the work is directed as it is fed to and past the needle; the object of the same being to produce an improved reversible gage which may be readily applied to the bed plate of the machine and worked in one position or another so as to increase the adaptability of devices of this character and permit the seamstress to amplify the distance from the edge of the work at which she can set the line of stitches.

This and other objects are accomplished by constructing the device in the manner hereinafter more fully described and claimed, and as shown in the drawings, wherein:—

Figure 1 is a front elevation of the bed of a sewing machine of ordinary type with this attachment applied,

Fig. 2 is a plan view of the same,

Fig. 3 is an enlarged perspective detail of the gage itself removed from the said plate and reversed end for end.

No claim for novelty is laid to the sewing machine, and we are concerned only with the needle N, presser foot P, the bed plate B having slides S which cover the shuttle (not shown), and the feed F which rises through the bed plate as usual. Guides or gages hitherto employed on the bed plates of sewing machines have been susceptible of adjustment toward and from the needle within certain limits, and by my improved construction I propose to amplify said limits while reducing the material in and therefore the cost of the gage itself. To this end I construct it preferably of sheet metal and substantially U-shaped in plan view, and I have used the numerals 1 and 2 to designate the front and rear arms which stand substantially parallel with and spaced from each other, and the numeral 3 to designate the cross bar connecting these arms at one end. Said cross bar is bent upward and preferably then again downward to form a rib 4 against which the edge of the work is to rest as it is fed forward under the needle N. A second element is the clip plate 5, also

stamped from sheet metal; and its size and shape are such that it may be well cut from the same piece of metal as that which is formed into the gage proper, being taken from that portion of the plate between the two arms. This plate 5 is a strap and is turned under into hooks 6 as best seen in Fig. 3 and its body provided with a longitudinal slot 7. A third element is a flat-headed screw 8 which is passed down through the slot 7 and engaged with a threaded hole in the bed plate B as will be clearly understood from Fig. 2, and when this screw is tightened into the hole it deflects or depresses the mid-length of the clip plate 5 slightly, as the thickness of its hooks 6 and the arms 1 and 2 will permit, and therefore causes the plate to clamp said arms with the result that the gage proper is prevented from slipping through the hooks or from turning on the bed plate B as long as the screw remains tight.

Fig. 2 shows the ordinary use of this device. The screw hole is so disposed in the bed plate B that the clip plate 5 stands as near the slides S as possible, and when the arms of the gage are passed through the two hooks 6, the rib 4 stands between the clip plate and the feed F and may be adjusted to permit a margin of perhaps two inches from the work beyond the seam being sewed by the needle, or by loosening the screw the rib 4 may be set up quite close to the feed and the needle. If a wider margin is desired, the screw is loosened and the entire device reversed so that the arms come astride of the feed and the needle and the rib then stands behind the clip plate as will be clear without further illustration. The arms may then be adjusted through the hooks as the rib is pushed back toward the rear and away from the feed so that quite a large margin beyond the line of stitching on the work can be gaged. When this device is not to be used at all, the screw 8 is withdrawn from the threaded hole in the bed plate B and the entire attachment loosened and then placed in the machine drawer. I have shown one of the arms as provided with graduation marks which, of course, might be applied to both arms or omitted entirely if preferred. The device will doubtless be nickelized or otherwise treated to make it attractive in appearance, and its proportions and details are not essential excepting that I would have its body U-shaped in contour so that

when it is reversed in position the arms will pass astride the feed and will not interfere with the pressure of the foot P upon the work.

5. What is claimed as new is:—
The herein described sewing machine gage comprising a substantially U-shaped element having an upstanding rib on its cross bar, and a sheet-metal clip plate having a longitudinal slot in its body for the reception of a set screw adapted to engage the

bed plate of the machine, its ends passing over the arms of said element and the extremities being bent under the same into hooks, for the purpose set forth.

15
In testimony whereof I affix my signature in presence of two witnesses.

MATTIE E. BLOOD.
